APPARATUS FOR LOWERING BURIAL
CASKETS INTO CRYPTSJohn B. Sinner and Oscar A. Sinner,
San Diego, Calif.

Application January 31, 1949, Serial No. 73,762

2 Claims. (Cl. 254—136)

1

Our invention relates to improvements in apparatus for lowering burial caskets into sub-surface crypts in mausoleums.

The primary object of our invention is to provide simply constructed, easily operated apparatus for lowering burial caskets into present-day sub-surface crypts smoothly with a minimum amount of labor, and which is substantially accident-proof.

Another object is to provide an apparatus of the character and for the purpose above set forth adapted for use in sub-surface crypts of different widths by easy, quick and accurate adjustment of the apparatus according to the width of the crypt.

Still another object is to provide such an apparatus which is comparatively inexpensive to manufacture, light in weight for easy handling, while strong and durable, and not liable to get out of order under prolonged use.

Other and subordinate objects, within the purview of our invention, together with the precise nature of our improvements will be readily understood when the succeeding description and claims are read with reference to the drawings accompanying and forming part of the specification.

In said drawings:

Figure 1 is a view in perspective of the carriage of our improved lowering apparatus in the preferred embodiment thereof;

Figure 2 is a view in plan of the track frame for the carriage drawn to a smaller scale;

Figure 3 is a fragmentary view in perspective of the track frame drawn to a larger scale;

Figure 4 is a fragmentary view in vertical longitudinal section illustrating the use of the apparatus in lowering a casket into a sub-surface crypt;

Figure 5 is a diagrammatic view in perspective of the cable winding and unwinding drum, the cables, and the pulleys therefor;

Figure 6 is a view in vertical transverse section taken on the line 6—6 of Figure 4 and drawn to a larger scale;

Figure 7 is a view in vertical transverse section taken on the line 7—7 of Figure 1;

Figure 8 is a similar view taken on the line 8—8 of Figure 4;

Figure 9 is another similar view taken on the line 9—9 of Figure 4.

Referring to the drawings by numerals, the apparatus of our invention is especially designed for use in lowering a burial casket 1, and, as illustrated in Figures 4, 8 and 9, into a sub-surface crypt 2 at one side of a corridor 3 in a conventional mausoleum 4. Such crypts 2 are

2

constructed with horizontal top ledges in the side walls thereof, for supporting a closure, not shown, and with a short front end wall 6, both said ledges and said end wall being above the level of the floor of the corridor 3.

The apparatus of our invention comprises a portable carriage 10 with crank operative casket lowering mechanism designated generally by the numeral 11 operative from a rear end frame of the carriage 10 and both constructed and arranged for transporting the casket out of the corridor 3 over the front wall 6 into lowering position over the crypt 2 with the rear end frame of the carriage positioned in the corridor 3 for operation of the lowering mechanism 11 by a person standing in the corridor at said end of the carriage 10.

The carriage 10 comprises an upright rear end frame 12 of inverted U-shape forming rear corner leg members 13 for the carriage 10 cross-connected by a cross bar 14 adjacent the lower ends thereof. A vertical, central, panel 15 is bolted to the cross bar 14 and to the top of said frame 12, for reinforcing purposes, and a further purpose presently seen.

A pair of horizontal side frames 16 extend forwardly from said rear end frame 12 and are suitably connected thereto, as by welding, not shown. The rear leg members 13 depend below the side frames 16 a distance slightly greater than the height of the front end wall 6 of the crypt 2 above the floor of the corridor 3 so that said frames 16 may be positioned horizontally over the top of the crypt 2 with the rear end frame 12 upright in the corridor 3.

The side frames 16 include upper and lower, parallel bars 17, 18 connected by front end uprights 19 from which depend front end corner leg members 20 for the carriage 10. The front leg members 20 are shorter than the rear leg members 13 to support the side frames 16 horizontally over the crypt 2 while said leg members 20 rest on the track frame presently described.

Relatively shorter, intermediate, horizontal bars 21 extend between the upper and lower bars 17, 18 of each side frame 16 and are spaced from the rear end frame 12 for a purpose presently apparent. Upright bars arranged in front and rear pairs 22, 23 adjacent the ends of the intermediate bars 21 connect said bars 17, 18, 19 of the side frames 16. The rear end frame 12 and the side frames 16 are constructed of tubular stock for combining strength and lightness in weight and the said side frames 16 are sufficiently resilient to enable the same to be sprung apart

at the front ends thereof for a particular purpose presently seen.

The front ends of the side frames 16 are adjustably connected together by a pair of tubular, aligned, horizontal cross bars 24, a rod 25 suitably fixed in and extending out of one cross bar 24 and slidably extending into the other of said cross bars, and a coupling pin 26 adapted to be extended through an aperture 27 in said rod 25 and, selectively, through pairs of apertures 28 in the cross bar 24 in which the rod 25 is slidably extended.

A pair of upper and lower cross bars 29, 30 connect the side frames 16 adjacent the rear end frame 12 to brace said frames.

As will be seen, by springing the side frames 16 apart forwardly of the cross bars 29, 30 and then connecting the same together by inserting the pin 26 in appropriate pairs of apertures 28 and through the apertures 27, the width of the carriage 10 may be varied at its front end in accordance with different widths of crypts 2 resulting, for instance, from structural variations.

Ball-type casters 31 are suitably socketed in the lower ends of the rear and front leg members 13, 20 so that the carriage 10 may be rolled easily in transporting a casket 1 into lowering position.

The lowering mechanism 11 comprises a flanged, hollow, drum 32 for winding and unwinding cables, presently described, and which is suitably fixed on the lower end portion of an upright shaft 33 journaled at its lower end in a drum supporting plate 34 extending horizontally between and suitably fixed to the cross bars 14, 31 in the longitudinal center of the carriage 10. The upper end of the shaft 33 is journaled in a gear frame 35 on the beforementioned panel 15. A worm gear 36 fast on the upper end of said shaft 33 in the gear frame 35, meshes with a worm 37 in said frame, fast on a horizontal worm shaft 38 journaled in said frame 35 and in the panel 15 with a hand crank 39 fast thereon in the rear of said panel 15 and the rear end frame 12.

A pair of relatively long and short cables 40, 41 are permanently connected, as at 42, to the drum 32 on one side of said drum. The other ends of said cables 40, 41 are provided with hooks 43 selectively insertable in circumferentially spaced apertures 44 in the drum 32 and in the side thereof opposite the connections 42, whereby the cables 40, 41 form loops with both ends arranged to be wound up on the drum 32 when said drum is rotated in one direction, said cables being adapted for unwinding at both ends when said drum 32 is rotated in the opposite directions. The hooks 43 and apertures 44 provide for shortening the loops formed by the cables 40, 41 for a purpose presently explained.

The cables 40, 41 are extended from the drum 32 toward opposite sides of the carriage 12 and trained around vertically spaced pulleys 45, 46 mounted in blocks 47 on the rear end frame 12 between the upper and lower bars 17, 18 of the side frames 12. From the pulleys 45, 46, said cables 40, 41 extend forwardly through complementary pairs of clamping blocks 47, 48 on uprights 49 extending between the upper and lower bars 17, 18 adjacent to the pulley blocks 47, 48. Thumb screws 50 provide for tightening the pairs of clamping blocks 47, 48 against said cables 40, 41 for a purpose presently seen.

From the clamping blocks 46, 47, the short cable 42 is trained forwardly around a pair of

pulleys 51 on the intermediate bars 21 at outboard sides of the side frames 16 so that the loop formed by said cable extends across the carriage 10 adjacent the rear end thereof, whereas, from the clamping blocks 47, 48 the long cable 40 is trained forwardly around a pair of pulleys 52 on the intermediate bars 21, at outboard sides of the side frames 16 so that the loop formed by said cable extends across the carriage 10 adjacent to the front end of the same.

As will now be seen, the long cable 40 forms a long loop which may be tightened by winding up on the drum 32 to support the casket 1 at one end thereof between the side frames 16 on the taut portion of said loop extending across said frame adjacent the rear end of the carriage.

Similarly, the short cable 42 forms a short loop which may be similarly tightened by winding up on the drum 32 to support the other end of the casket 1 on a taut portion of the short loop extending across the carriage 10 adjacent the rear end of said carriage. Also, as will be clear, by rotating the drum 32 in the proper direction, the long and short cables 40, 42 may be unwound, uniformly, to lower the loops, under the weight of the casket 1, uniformly, between the pairs of pulleys 52, 51 to thereby lower the casket 1 uniformly at both ends.

A rectangular track frame 55 is provided to fit in the crypt 2 on the ledges 5. The track frame 55 is provided with side angle tracks 56 for resting on said ledges and along which the casters 31 of the front leg members 20 may be rolled in transporting the casket 1 into lowering position, said track frame preventing the casters 31 from scraping against the sides of the crypt 2 above said ledges 5. Pairs of links 57 at the ends of the track frame 55 are pivoted at outer ends thereof, as at 58, to said tracks 56 with the inner ends of the links 57 of the pairs pivoted together, as at 59, so that the pairs of links 57 may be swung into parallel side by side relation to fold the tracks 56 side by side and parallel, so that the track frame 55 may be completely folded for carrying or storage when not in use. The pairs of links 57 are swingable relatively into unfolded, aligned, relation to unfold the track frame 56, as will be clear. A stop lug 60 on one link 57 of each pair engages the other link of the pair and establishes the unfolded position of the pairs of links 57, and hence the unfolded position of the track frame 55. One link 57 of each pair is provided with longitudinally spaced apertures 61 for insertion of its pivot 59 selectively therethrough to vary the width of the track frame 55, when unfolded, in accordance with different width of crypts 2.

The manner in which the described invention is desired to be used and operated will be readily understood. With the cables 40, 41 wound up on the drum 32 to tighten the loops formed thereby, the pairs of clamping blocks 47, 48 may be tightened by the thumb screws 50 against said cables to maintain taut the portions of the loops on said cables extending across the carriage 10. The casket 1 may then be placed on the taut portions of said loops for transporting by the carriage 10. With the track frame 55 positioned on the ledges 5, the carriage 10 may be grasped by the side frames 17, wheeled along the corridor 3 with the rear end frame 12 rolling along the floor of the corridor and the front end of the carriage 10 held elevated to maintain the casket 1 level. The carriage 10 may then be rolled or wheeled to the crypt 2 and its front end disposed on the track

frame 55 by means of the front leg members 20 so that the casters 31 of said leg members will roll along the track bars 56 with the rear frame 12 rolling on the floor of the corridor 3. The carriage 10 may then, by using the top of the frame 12 as a handle bar, be shoved forwardly into the position shown in Figure 4 to dispose the casket 1 over the crypt 2 into lowering position with the rear end frame 12 disposed in the corridor 3 for easy access to the crank 39. Then, with the hand crank 39 held stationary, the clamping blocks 47, 48 may be loosened and said crank operated to rotate the drum 32 in the proper direction to unwind the cables 41, 42 and lower the casket 1, in the manner already described, into the crypt 2. The hooks 43 may then be disconnected from the drum 32 and said drum rotated in a winding up direction to retrieve the cables 41, 42 for attachment of the hooks 43 in selected apertures 44, for repeat operations. Should slack occur in either tightened cables 41, 42, this may be taken up by attaching the appropriate hook 43 in a selected aperture 44 to shorten the loops formed by the cable in which such slack has occurred.

The foregoing will, it is believed, suffice to impart a clear understanding of our invention, without further explanation.

Manifestly, the invention, as described, is susceptible of modifications, without departing from the inventive concept, and right is herein reserved to such modifications as fall within the scope of the appended claims.

Having described the invention, what is claimed as new is:

1. Apparatus for lowering a burial casket into a sub-surface crypt comprising a substantially rectangular carriage for positioning in the top of the crypt comprising an upright end frame and horizontal opposite side frames, cable winding and unwinding means on said carriage adjacent said end frame including a drum, a pair of cables, connections between both ends of said cables and said drum for winding said cables up and unwinding the same in the form of loops, and pairs of opposite pulleys on said side frames around which said loops are trained to be stretched taut across said carriage adjacent opposite ends thereof by winding up said cables to thereby support a casket elevated above said crypt, said

cables being guided by said pulleys during unwinding thereof to provide descending loops between the pairs of pulleys for lowering the casket into said crypt, said connections comprising 5 hooks attachable at circumferentially spaced points on said drum for adjusting the length of the loops formed by said cables.

2. Apparatus for lowering a burial casket into a sub-surface crypt comprising a substantially rectangular carriage for positioning in the top of the crypt comprising an upright end frame of inverted U-shape forming a top handle bar, pairs of upper and lower side bars extending from said frame below said handle bar, cable winding and unwinding means on said carriage adjacent said end frame, a pair of cables having both ends connected to said means for winding said cables up and unwinding the same in the form of loops, pairs of opposite pulleys mounted on said upper and lower side bars between the bars of the pairs and around which said loops are trained to be stretched taut across said carriage adjacent opposite ends thereof by winding up said cables to thereby support a casket elevated above said crypt, said cables being guided by said pulleys during unwinding thereof to provide descending loops between the pairs of pulleys for lowering the casket into said crypt, and means for releasably holding said cables pulled tight independently of said means first named comprising cable clamps interposed between the upper and lower side bars of said pairs and fixed thereto.

JOHN B. SINNER.
